UNITED STATES PATENT OFFICE.

CHARLES BENJAMIN MAXSON, OF WESTERLY, RHODE ISLAND, ASSIGNOR OF ONE-HALF TO JULIAN W. MAXSON, OF WESTERLY, RHODE ISLAND.

FEEDING AND CUTTING MECHANISM.

Original application filed September 25, 1923, Serial No. 644,775. Divided and this application filed August 22, 1924. Serial No. 733,523.

The present invention relates to feeding and cutting mechanisms, and its chief aim is to provide an improved mechanism for intermittently feeding and cutting objects like 5 paper. Other purposes of the invention will appear hereinafter.

The invention will be fully explained in connection with the accompanying drawings, in which Fig. 1 is a plan of a mechanism constructed according to a preferred embodiment of the present invention; Fig. 2 is a side elevation of the same; Fig. 3 is a section taken upon the line 3—3 of Fig. 1, looking in the direction of the arrows; Fig. 15 4 is a front elevation of the mechanism shown in Figs. 1 and 2; Fig. 5 is a fragmentary diagrammatic view illustrating one application of the invention; and Fig. 6 is a view of a detail.

20 The present invention is illustrated in the accompanying drawings in connection with a machine for feeding and delivering paper sheets, and for marking or separating the sheets so delivered into bundles or reams, 25 each containing a predetermined number of the sheets. The said machine constitutes the subject matter of a copending application, Serial No. 664,775, filed September 25, 1923, of which the present application is a division. The sheets are fed by tapes 18 and 20 into a lay-boy 4, which is automatically lowered from time to time to maintain approximately uniform the level of the sheets that are stacked therein. As they are delivered 30 into the lay-boy 4, the sheets are automatically counted; and thin, paper tags 24 are automatically inserted between adjacent, predetermined sheets at the completion of each count to separate or mark the bundles 35 or reams of sheets so delivered and counted. The tags 24 are automatically cut off from a paper strip 34 that is intermittently unwound from a reel 36. The present invention is more particularly concerned with the 40 mechanism for feeding and cutting the paper strip 34.

Feed rolls 26 and 27 automatically advance intermittently, through a curved guide 28, and between a movable knife 30 and a 45 stationary knife 32, the paper strip 34 as it is unwound from the reel 36. The end 38 of the paper strip is thus intermittently advanced, at the proper time, and becomes inserted between adjacent sheets 104 and 106, 50 Fig. 5, of the stack and, after it is severed

by the knives 30 and 32, constitutes a tag 24. The feed roll 26 is mounted upon an end of a bell-crank lever 40, intermediately pivoted at 41, and the other end of which is spring pressed at 42 to cause the feed roll 60 26 to maintain the paper strip tightly in engagement with the feed roll 27. The feed rolls 26 and 27 are provided with meshing gears, as shown. To advance the strip 34, therefore, it is necessary to rotate intermittently the feed roll 26 only, the feed roll 27 being positively driven by its gear from the feed roll 26, and the two rolls positively pulling the strip 34 through between them.

The feed rolls 26 and 27 are situated at 70 the rear end of the guide 28, at a point just to the rear of and just below the upper sheets of the stack of sheets in the lay-boy, and the knife 32 is situated at the other end. A shaft 44, situated to the rear of the guide 75 28, is provided with a gear 126, keyed thereto at 220, which drives the feed rolls 26 and 27 through a train of gearing 128. The train of gearing 128 makes it possible to position the feed rolls 26 and 27 properly, 80 at a distance from their driving shaft 44. By feeding the strip at a point so close to the stack, there is no tendency for the strip to buckle or sag in the guide 28. This obviates danger of the strip getting stuck in the guide, which would prevent the strip from being advanced at all. A lever 31, pivoted at 33, by its own weight presses the strip 34 against a seat 35 in the bell-crank lever, just to the rear of the feed rolls 26 85 and 27, the better to guide the strip. The shaft 44 may be intermittently rotated by a continuously rotating pawl (not shown) as is described in the above-mentioned application, or in any other desired manner, at the 90 end of a cycle of operation of a counter (not shown),—say, after a ream has been delivered and counted. The end 38 of the strip 34 is thereupon rapidly fed from the rear of the stack, in a direction at a substantial angle 95 to the horizontal direction of feed of the sheets, shown nearly vertical in Fig. 2, into the path of feed of the next following sheet, which constitutes the first sheet 106 of the next ream. If the end 38 of the strip were 100 fed horizontally forward, or at an angle not sufficiently far from the horizontal, being constituted of thin paper, it might strike the rear of the stack of sheets, and not enter 105 between adjacent sheets at all, thus falling 110

to the floor and failing to mark the separating line between the reams. If fed at an angle so near to the horizontal, furthermore, the tags, if it is succeeded in getting them inserted between the sheets, are frequently carried by the sheet 106 so far in between the sheet 104 and the sheet 103 that it is lost to view, and its function as a marker becomes lost. It is therefore desirable to feed 10 the end 38 of the strip 34 at a substantial enough angle to the direction of feed, so as to avoid having the strip engage the rear of the stack or to become lost between sheets of the stack. If fed at such angle into the 15 path of feed of the sheet 106, the head of the sheet 106 will be sure to strike it and lay it down flat upon the last sheet 104 of the ream just completed; which is readily effected by the thin, flexible character of the 20 strip 34. All possibility of the end 38 of the strip 34 becoming displaced is thus avoided. It is furthermore unnecessary to time accurately the moment when the end 25 of the strip is fed upward, as would be the case if it were fed horizontally, or nearly so, which timing it is necessary to adjust for sheets of different length. In order to insure feeding the strip at such angle, an intermediate portion of the guide 28 is curved, 30 as shown, so as to rise nearly vertically, as illustrated in Fig. 2 at 29. The end 38 of the sheet is fed upward for a distance sufficiently great so as to make sure that it will rise above the top sheets of the stack and into 35 the path of travel of the sheet 103.

When the end 38 has thus been laid flat by the sheet 106 upon the sheet 104, it is still too early to sever it from the strip 34, as the severing process might pull it out of place. 40 It is preferable to wait until a number of sheets have been fed forward over the sheet 106; their combined weight then serving to hold the end 38 of the strip 34 in place while it is severed. This feature of the operation 45 is not illustrated or further described herein, because unnecessary to an understanding of the present invention. A full disclosure will be found in the above-identified application.

50 The mechanism for operating the knife 30 will now be described. The knife 30 is adapted to be reciprocated in a vertical plane in guides 108, to cooperate with the stationary knife 32, by a lever 110, one end of which 55 is pivoted at 114 and to the other end of which the knife is connected at 112. An intermediate portion 116 of the lever 110 is adapted to be engaged by a rotary cam 118. At a predetermined point in the operation 60 of the shaft 44, the lever 110 is actuated by the cam 118, in opposition to the force exerted by a spring 120, to move the knife 30 upward, as seen in Figs. 2 and 4, causing the end 38 to become severed from the strip 34. 65 It will be noted, from Figs. 1 and 4, that the

knives 30 and 32 are inclined to each other in two planes, so as to provide a very effective, shearing cut and a spring-pressed plunger 55 yieldingly maintains the movable knife 30 biased towards the knife 32, so as 70 to be in the most suitable position for effecting such cut. The roll cam 118 is mounted upon a shaft 123 having a gear 124 among the same train of gearing 128 that drives the feed rolls 26 and 27 from the shaft 44. The 75 knife is thus operated in timed relation to the operation of the feed rolls 26 and 27 by the shaft 44, which first operates through nearly a complete revolution to cause the feed rolls to feed the strip 34, and then remains stationary until the desired number of sheets have been fed over the sheet 106, and which finally operates through the remainder of its revolution to cause the roll cam 118 to engage the lever 110, thereby causing the knife to sever the end 38 from the strip 34. The knife is returned to normal position before the shaft 44 comes to rest. The cam roll 118 is adjustable to adjust the time of 80 operation of the knife 30.

Upon the retreat of the movable knife 30, the new end 38 of the strip 34 is left under the stationary knife 32. Owing to the substantially vertical direction of feeding movement of the end 38 of the strip, there would be a tendency for the strip to strike against the knife 32, and prevent further advance of the end of the strip, at the next feed movement of the feed rolls 26 and 27. To prevent this happening, a lever 37 is adapted to pivot, by its own weight, about a pivotal point 39, so as to enter between the two knives 30 and 32, thereby engaging the end 38 of the strip and pushing it forward, beyond and between the knives. The next 100 forward feed movement of the feed rolls 26 and 27 will therefore result in advancing the end 38 of the strip in a nearly vertical direction, as before described, and as illustrated more particularly in Fig. 2, to one side of the cutter 32. Though the cutter 32 is thus situated in the vertical path of feed, it does not interfere with the feeding because of the deflecting action of the lever 37. The lever 105 37 is forced out of the way of the movable knife 30, at each upward movement of the same, in any desired manner, as by means of a cam (not shown, but illustrated and described in the above-named application) 110 upon the inner face of the knife 30 that is 115 adapted to engage the lever 37 when the knife is moved upward, and that is adapted to become disengaged from the lever 37 on the downward movement of the knife. The use of the said cam is, in practice, found to 120 be unnecessary, as the knife 30 may force the lever 37 out of the way by direct engagement with its projecting portion. If the lever 37 is constituted of soft metal, like lead, 125 it will not dull or otherwise injure the knife. 130

The return gravity movement of the lever is limited by an integral projection 53 that is adapted to engage the rear of the knife 32.

The end 38 of the strip is thus automatically advanced into position in a direction nearly at right angles to the direction of feed of the sheets so that it may be struck by the first sheet 106 of each new ream and laid flat thereby between adjacent sheets 104 and 106 of adjacent reams, and it is then severed from the strip 34, the tag 24 being thus left in place to mark the boundary between the two reams.

It is desirable that the feed rolls 26 and 27 be ineffective to feed the strip 34 during the cutting operation of the knife, as further feeding of the strip 34 would cause it to buckle. The feed roll 26 is therefore provided with a flattened portion 43, shown more particularly in Fig. 3. During the operation of the cam 118, the flattened portion 43 of the feed roll 26 occupies a position opposed to the lower portion of the feed roll 27. The flat portion 43 is maintained out of engagement with the feed roll 27 by the gears of the feed rolls 26 and 27 acting on one side, and a corresponding collar-like segment 61 integrally provided at the opposite side of the feed roll 26, and which engages the feed roll 27 under the influence of the spring 42. The flattened portion 43, in fact, is produced by cutting away a portion of the cylindrical surface of the feed roll 26 between the collar-like segment and its oppositely disposed gear. Further feeding of the strip 34 is at this time, therefore, rendered impossible. To render the feed rolls 26 and 27 ineffective at all times, the bell-crank lever 40 may be engaged by a stop 47 of a member 45, thereby overcoming the force of the spring 42. The member 45 may be pivotally actuated into and out of engagement with the bell-crank lever 40 about a pivotal point 51. Only when the member 45 is moved about its pivotal point 51 wholly out of the way are the feed rolls 26 and 27 effective to feed the strip 34.

The marker may be operated from the shaft 122 instead of from the shaft 44. It may be desirable to operate the shafts 44 and 122 selectively, the shaft 44 from a 500-sheet-ream counter and the shaft 122 from a 480-sheet-ream counter. To operate the marker from the shaft 122, the key 220, Fig. 2, is removed, so as to render the gear 126 loose upon the shaft 44, and a gear 224, that is loose when the gear 126 is keyed to the shaft 44, is keyed at 222 to the shaft 122 instead. Rotation of the shaft 122, through an idler gear 125, will thus drive the feed rolls 26 and 27 through the same train of gearing 128, the gear 126 now rotating idly on the shaft 44. The idler gear 125 enables the gears 124 and 126 to drive the feed rolls 26 and 27 in the same direction. The feed

rolls 26 and 27 are thus operated to feed the strip 34 in the same manner as before described, except that they are now operated from the shaft 122 instead of from the shaft 44; and the knife-controlling-cam wheel 118 still operates to control the knife, as before described.

It will be understood that the invention is not limited to the exact embodiment that is herein illustrated and described, and is subject to modification and change by persons skilled in the art. All such modifications and changes are considered to be within the spirit of the invention, and the scope of the invention is defined by the appended claims.

What is claimed is:

1. A machine of the class described having, in combination, a cutter, means permanently situated at a predetermined point for feeding material in a predetermined direction towards the cutter so as to tend to cause the material to engage the cutter, and means for deflecting the material from the predetermined direction out of the way of the cutter.

2. A machine of the class described having, in combination, a cutter, means permanently situated at a predetermined point for feeding a strip in a predetermined direction from the predetermined point towards the cutter so as to tend to cause the strip to engage the cutter, and means for deflecting the strip from the predetermined direction out of the way of the cutter.

3. A machine of the class described having, in combination, a guide, means for feeding material in the guide, a cutter fixed to the guide in the path of feed of the material, and means for deflecting the material out of the way of the cutter.

4. A machine of the class described having, in combination, a stationary cutter, a movable cutter, means permanently situated at a predetermined point for feeding a strip in a predetermined direction from the predetermined point towards the stationary cutter so as to tend to cause the strip to engage the stationary cutter, and means for deflecting the strip from the predetermined direction out of the way of the stationary cutter.

5. A machine of the class described having, in combination, a curved guide, a cutter situated on one side of the curve of the guide, means for feeding material to the cutter situated on the other side of the curve of the guide, whereby the material, upon being fed through the curved guide, is adapted to engage the cutter, and means for deflecting the material out of the way of the cutter.

6. A machine of the class described having, in combination, a curved guide, means for feeding material in the guide, a cutter situated on one side of the curve of the guide

in the path of feed, a cooperating cutter, the cutters being relatively movable towards and from each other, and means for deflecting the material out of the way of the first-named cutter and in between the first-named cutter and the cooperating cutter.

7. A machine of the class described having, in combination, means for feeding material, a cutter situated in the path of feed, whereby the feeding means tends to cause the material to engage the cutter, a cooperating cutter relatively movable towards and from the first-named cutter, means for deflecting the material out of the way of the first-named cutter and in between the first-named cutter and the cooperating cutter, and means controlled by one of the cutters for controlling the deflecting means.

8. A machine of the class described having, in combination, two cooperating cutters, means for feeding a strip in a direction such as to tend to cause the strip to engage one of the cutters, means for deflecting the strip out of the way of the said one cutter, and means controlled by the other cutter for controlling the deflecting means.

9. A machine of the class described having, in combination, means for feeding material, a cutter situated in the path of feed, a cooperating cutter relatively movable towards and from the first-named cutter, a member adapted to enter between the two cutters to deflect the material out of the way of the first-named cutter, and means controlled by one of the cutters for moving the member away from between the two cutters.

10. A machine of the class described having, in combination, a stationary cutter, a movable cutter, means for feeding a strip in a direction such as to tend to cause the strip to engage the stationary cutter, a lever adapted to enter between the two cutters to deflect the strip out of the way of the stationary cutter, and means controlled by the movable cutter for moving the lever away from between the two cutters.

11. A machine of the class described having, in combination, a pivoted lever, a feed roll mounted on the lever, means for driving the feed roll, a cooperating feed roll, means for yieldingly maintaining the feed rolls in engagement, the lever having a guide for the material to be fed, and means for maintaining the material in the guide.

12. A machine of the class described having, in combination, a feed roll, two means each individually adapted to drive the feed roll, a gear connecting the feed roll with one of the driving means, and a gear connecting the connecting gear with the other driving means.

13. A machine of the class described having, in combination, a curved guide, means situated at one end of the curve of the guide for feeding material in the guide, a cutter

situated at the other end of the curve of the guide in the path of feed, a cooperating cutter, the cutters being relatively movable towards and from each other, means for deflecting the material out of the way of the first-named cutter and in between the first-named cutter and the cooperating cutter, means for driving the feeding means and relatively actuating the cutters, and a train of gearing connecting the feeding means and the cutters with the driving means.

14. A machine of the class described having, in combination, a bell-crank lever, a feed roll mounted upon one arm of the lever, a cooperating feed roll, means yieldingly engaging the other arm of the bell-crank lever to yieldingly maintain the feed rolls in engagement, means for driving the feed rolls, one of the feed rolls having a depressed portion, and means for maintaining the depressed portion out of contact with the other feed roll.

15. A machine of the class described having in combination, means for feeding material, a cutter situated in the path of feed, whereby the feeding means tends to cause the material to engage the cutter, and means for engaging the material and for moving the engaged material out of the way of the cutter.

16. A machine of the class described having, in combination, a stationary cutter, a movable cutter, means for feeding a strip in a direction such as to tend to cause the strip to engage the stationary cutter, and means for engaging the strip and for moving the engaged strip out of the way of the stationary cutter.

17. A machine of the class described having, in combination, feed means, a cutter, a cam for actuating the cutter, means for driving the feed means, a gear for driving the cam, and a train of gearing connecting the feed means with the driving means and comprising the cam driving gear.

18. A machine of the class described having, in combination, means for feeding material, a cutter situated in the path of feed, means for deflecting the material out of the way of the cutter, means for driving the feed means and the cutter, and a train of gearing connecting the feed means and the cutter with the driving means.

19. A machine of the class described having, in combination, a bell-crank lever, a feed roll mounted upon one arm of the lever, a cooperating feed roll, means yieldingly engaging one side of the other arm of the bell-crank lever to yieldingly maintain the lever in a position such that the feed rolls shall be maintained in yielding engagement, and means for engaging an opposite side of the other arm for rendering the yielding maintaining means ineffective.

20. A machine of the class described hav-

ing, in combination, two feed rolls for feeding material, means for rotating one of the feed rolls through a portion of a revolution to feed the material and for thereupon maintaining the feed rolls against rotation to prevent further feeding of the material, and means whereby the said one feed roll may

then be rotated through another portion of a revolution without feeding the material.

In testimony whereof, I have hereunto 10
subscribed my name this 31st day of July,
1924.

CHARLES B. MAXSON.
